US00D789968S

(12) United States Design Patent (10) Patent No.: US D789,968 S
(45) Date of Patent: * Jun. 20, 2017

(54) DISPLAY SCREEN OR PORTION THEREOF
WITH A GRAPHICAL USER INTERFACE WITH ICONS

(71) Applicant: DexCom, Inc., San Diego, CA (US)

(72) Inventors: Michael Robert Mensinger, San Diego, CA (US); Eric Cohen, San Diego, CA (US); Phil Mayou, San Diego, CA (US); Eli Reihman, San Diego, CA (US); Katherine Yerre Koehler, San Diego, CA (US); Rian Draeger, San Diego, CA (US); Angela Marie Traven, San Marcos, CA (US)

(73) Assignee: Dexcom, Inc., San Diego, CA (US)

() Term: 15 Years

(21) Appl. No.: 29/577,019

(22) Filed: Sep. 8, 2016

Related U.S. Application Data

(60) Division of application No. 29/495,687, filed on Jul. 2, 2014, now Pat. No. Des. 767,605, which is a continuation-in-part of application No. 13/842,679, filed on Mar. 15, 2013.

(57) CLAIM

The ornamental design for a display screen or portion thereof with a graphical user interface with icons, substantially as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 shows a front view of a display screen or portion thereof with a graphical user interface with icons that incorporates the new, original, and ornamental design; and, FIG. 2 shows a front view of a display screen or portion thereof with a graphical user interface with icons that incorporates the new, original, and ornamental design. The broken lines in the figures illustrate a display screen or portion thereof and form no part of the claimed design.

1 Claim, 2 Drawing Sheets
